UNITED STATES PATENT OFFICE.

FRITHIOF N. JOHNSON, OF WAUKEGAN, ILLINOIS.

SPRING-MATTRESS.

1,250,892.

Specification of Letters Patent. Patented Dec. 18, 1917.

Application filed August 26, 1916. Serial No. 117,035.

To all whom it may concern:

Be it known that I, FRITHIOF N. JOHNSON, a citizen of the United States, and a resident of Waukegan, in the county of Lake and State of Illinois, have invented certain new and useful Improvements in Spring-Mattresses, of which the following is a specification.

This invention relates to devices designed to be used in vehicles, as a cushion to the seat thereof, and in beds, as a mattress, and in other like places.

The objects of the invention are to obtain a spring mattress in which the springs will necessarily retain the position in which they are originally arranged, without the use of ties or other connecting devices; a mattress which will be durable and retain its shape; and a device which will have a comfortable feeling to the person using the same.

I have illustrated a spring mattress embodying this invention which is particularly adapted to form the cushion of a seat in an automobile, in the drawing accompanying and forming a part of this specification; and in said drawing—

Figure 1 is a top plan view, with the upper coverings removed at the right hand end thereof, to expose the arrangement of springs to view.

Fig. 2 is a side elevation of the device illustrated in Fig. 1, with the side coverings removed at the right hand end thereof to expose the springs to view.

Fig. 3 is a plan view of one end of the covering adjacent to the springs of the device, showing the manner of stitching the same, with the springs not inserted in place.

And Fig. 4 is a view of the edge, looking down, of the covering which is illustrated in Fig. 3.

A reference character applied to designate a given part indicates said part throughout the several figures of the drawing wherever the same appears.

In constructing a spring mattress embodying this invention two strips of canvas, or other suitable material, as heavy woven fabric, sometimes called duck, or ducking, (represented by letter A) are placed to register, and the stitching B is made, to join said parts together, and at the same time to obtain pockets, (indicated by letter C). The length of the strips are made to correspond with the length of the mattress which is to be made, or with the width of said mattress,

as preferred; and after the stitching B is completed the springs D are inserted in said pockets. These springs are ordinary spiral springs having one end thereof larger than the other (in diameter), and hence, when they are inserted in pockets C one thereof will be inserted at the larger end of a pocket, from one edge of material A, and the next spring will be inserted in the adjacent pocket from the other edge of said material. When the several pockets which are obtained by stitching B are filled in the manner last above described the upper and lower edges of said strips are brought over on to said springs and secured together, covering the ends of said springs, as is illustrated at 12, Fig. 1. e, e are the edges of the strips before being turned over on to the springs, (see Figs. 2 and 3).

A plurality of strips A having been stitched at B, the springs inserted, as described, and the edges of pockets C having been turned on to the springs and secured together, a plurality of like constructions are arranged parallel to each other, and close together, with the larger ends of the springs in one construction adjacent to the smaller ends of the springs in the adjacent construction; and said constructions are provided with an additional cover which is made of suitable flexible material, as canvas, ducking, leather, or the like.

The additional cover is represented by the upper and lower faces F, F', sides f, f, and the metal frames G, G'. The metal frames G, G' extend entirely around said additional cover, (ends f, f', as well as sides f, f). The metal frames are made by me of wire, the function thereof being to hold the several constructions formed by the strips A having pockets C and springs D in said pockets, in suitable relative relation when the mattress is being moved about, and not resting on the seat of the vehicle.

An additional cover to the one comprising faces F, F', sides f, f, ends f, f', and frames G, G', may be placed over said described cover; but as said additional cover is not an essential part of the mattress embodying the invention I have not illustrated it, or described its construction.

In constructing and using spring mattresses embodying this invention I find that adjacent rows of springs, inclosed in pockets as described, fit to each other in the same

manner that adjacent springs fit in said pockets; and that the relative positions of the springs are not changed by use of the device.

5 By reference to Fig. 1, of the drawing, it will be observed that the end spring of each construction or unit, is close to the end of the mattress or cushion; all the springs of the units being in the same lateral line with 10 the springs of adjacent units, and hence, each unit has the same number of springs in it.

The springs of adjacent rows fitting to each other in the same manner as the adjacent springs in a given unit, the springs of 15 one row cannot get out of said described position relative to the springs in adjacent rows, and no tying of the springs of one row to the springs of adjacent rows is required. It is also obvious that the springs 20 of one row being in line laterally with the springs of adjacent rows a larger number of springs are contained in a mattress or cushion of a given size than could be contained in said mattress or cushion were the 25 springs of one row alternate with the ones of adjacent rows.

I claim;

1. A mattress comprising a cover, and a plurality of units arranged therein, each of 30 said units consisting of strips of textile material stitched at intervals to form pockets

respectively having one end larger than its other end, and with the large end of one pocket in the same plane as the small end of the adjacent pocket, spiral springs in said 35 pockets, the ends of said spirals corresponding with the ends of said pockets, and means to close the ends of said pockets, said units positioned in said cover with adjacent 40 springs in adjacent units fitting together in the same manner as do adjacent springs in each unit.

2. A spring mattress comprising a plurality of units, each of said units consisting of a cover provided with cone-shaped pockets, in combination with spiral springs assembled in said pockets, one end of said 45 springs being larger than the other and the small end of one spring in each of said units being in substantially the same plane as the large end of the adjoining spring, and an additional cover adapted to hold 50 said plurality of units, said units being assembled in said additional cover with the small end of a spring in one unit in the 55 same line and in substantially the same plane as the large end of the spring beside it in the adjoining unit.

FRITHIOF N. JOHNSON.
